7 Claims. (Cl. 248—357)

1

This invention relates to improvements in or relating to sockets for pit props. As is known, in present-day mining practice as a rule only the immediate working sites are protected against collapse by supporting the roof by means of appropriate frames which generally consist of wooden cross-pieces arranged in layers, in which are incorporated steel sockets. These are so constructed as to make possible subsequent collapse of the frame under pressure of the earth. For this purpose these sockets consist at least of two wedge members mounted slidably one above the other, which are releasably connected in the "use" position by a coupling rod so that by releasing the coupling, the upper wedge member, under its own weight and the pressure bearing on it, slides down on the oblique face of the lower wedge member with corresponding acceleration, and the cross pieces carried thereby and the whole frame-work collapse. In order to prevent undesired premature automatic release of the coupling, for instance when the sockets are worn, the coupling rod is locked by a special locking member against an upward movement, leading to uncoupling, of the head of the coupling rod which projects from the front face of the upper wedge member.

In a known form of construction this locking member consists of a bar passing into a guideway in the upper wedge member above the coupling rod. In order to release the locking device, this bar must first be withdrawn before the coupling rod can be lifted by a blow on the underside of the projecting head of the coupling rod, which can be delivered by means of a suitable tool from a safe distance from the socket in question so that the operator is not involved in the subsequent collapse of the frame. Since, however, as already mentioned, particularly with worn sockets or with very high pressure, an automatic release of the coupling on failure of the locking lies within the region of possibility, the above-mentioned unlocking procedure is of course associated with the danger of an immediately following undesired uncoupling. Withdrawal of the said bar which is necessary for unlocking, which may be rendered almost impossible by eventual pressure on the coupling rod, means that the bar must be grasped directly by the hand of the operator, so that the latter must remain during this process in the immediate neighbourhood of the socket in question and may not be able to withdraw himself sufficiently quickly to avoid being involved in a subsequent collapse of the frame due to an immediately following undesired uncoupling.

It is an object of the present invention to avoid the above-mentioned disadvantages.

The present invention provides a socket for a pit prop comprising two wedge members slidably

10 mounted one above the other, which are releasably coupled together in the use position by a coupling rod which after release of the locking member is movable into the uncoupling position by raising the head of the coupling rod which projects from the front face of the upper wedge member, characterised in that the head of the coupling rod is provided with a control member which co-operates with a locking member and projects from the underside of the head of the coupling rod when the locking member is engaged, the whole arrangement being such that by 15 striking a blow on the underside of the head of the coupling rod is first unlocked by driving up the control member and thereafter the coupling is disengaged.

20 By means of the above described arrangement it is possible to release the locking device in exactly the same way as uncoupling is carried out, that is to say, from a safe distance, and to perform both operations one after the other in one and the same operation.

25 The accompanying drawings show an embodiment by way of example of the invention, which embodiment also possesses further advantages compared to the known method of construction as will be seen from the description which follows.

In the drawings,

30 Fig. 1 shows a side view of the socket in median section in the use position,

Fig. 2 shows a side view after uncoupling has taken place and the upper wedge member has slid down, and

Fig. 3 shows a plan view corresponding to Fig. 2 partly in section.

35 Referring now to Fig. 1, the lower wedge member 2 set on the beam 1 carries on its oblique wedge face 3 the upper wedge member 4 which rests with its oblique margins 5 on the said guideway 3. As may be seen from Fig. 3 the guideway 3 is pierced by a central longitudinal slot 6 which is bridged over in its upper part by the cross piece 7. In this slot 6 the coupling rod 8 is mounted to rock in a vertical plane about a securing bolt 9 by means of its own bearing eye 11. The bolt 9 is mounted in the bearing eyes 10 provided in the rear of the lower part 2. This bearing eye 11 of the coupling rod 8 is provided above with a nose 11', which co-operates with the rear side of the crosspiece 7.

40 The floor 12 of the upper wedge member 4 is provided in median longitudinal section (see Fig. 3) with a guideway 13 which extends partly also into the rear wall 14 and through which the coupling rod 8 passes. The end of the coupling rod 8 is provided with a head 15. The slot 6 and the opening 13 are made narrower than the head 15 so that in the position of the parts shown in Figs. 2 and 3, the head serves to retain the upper 45 wedge member 4.

The front face 16 of the upper wedge member 4 is provided below with two projecting lugs 17 which form a continuation of the boundary walls of the slot 12 and the front edges 17' of which in the use position of the parts shown in Fig. 1 form an abutment for the shoulders 15' of the head 15, so that in the position shown in Fig. 1 the two wedge members 2 and 4 are coupled by the coupling rod 8 and thereby the upper wedge member 4 is prevented from sliding down.

On the front face 16 two bearing eyes 18 are arranged symmetrical to the slot 12, between which eyes is disposed a locking member 19 pivoted to a bolt 18', which locking member in the position shown in Fig. 1 is supported in compression in a slotted depression formed in the lower end of the head 15 of the coupling rod. The head 15 is provided in the area of the slotted supporting part with an opening 20 in which is inserted a bolt-shaped control member 21 which can be raised and depressed therein. The control member 21 lies under its own weight with its upper head on an intermediate collar 22 in the opening 20 and projects with its lower head from the lower face of the head 15. As can be seen it is so formed that on being driven up through the opening 20 it forces the locking member 19 out of engagement with the head 15 of the coupling rod.

If then, starting from the use position shown in Fig. 1, a blow is struck on the lower side of the head 15, then this operation first drives up the control member 21 and thereby drives up the locking member 19, whereby the coupling rod 8 is released. When the control member 21 has been fully driven in, the blow acts directly on the lower face of the head 15 whereby the coupling rod is rocked upwards about the bolt 9. As a result the shoulders 15' of the head 15 are withdrawn from the lugs 17 whereby coupling between the two wedge members 2 and 4 is released. The upper wedge member 4, as a result of its own weight, and of the pressure of the prop resting on its top face 23, slides down over the slideway 3 with a corresponding acceleration, and is arrested with the rear wall 14 and the parts of the floor 12 adjacent the slot 13 against the said shoulders 15' of the head 15, so that the upper wedge member 4 must remain in the immediate neighbourhood of the lower wedge member 2, and cannot, as was the case with known constructions of previous sockets, be hurled far away by the kinetic energy acquired in its downward sliding and thus be lost and lead to risks. It has been found that even connecting the two wedge members together by a chain as a precaution against this hurling away is not sufficient, since in certain circumstances such a chain can be broken.

In order now to protect the bolt 9, to which the coupling rod 8 is secured, against deformation or eventual shearing when large pressures arise, the bolt 9 is relieved of load by the nose 11' bearing against the rear edge of the cross piece 7 of the lower wedge member 2 when the parts are in the position shown in Figs. 2 and 3. This nose 11' is made so massive that it can take up all the forces arising without overstressing. This is also of importance because the bolt 9 serves also for other purposes, namely for connecting the two adjacent sockets by means of a distance rod, so that the bolt 9 is also exposed to other forces. In this case, however, the cross piece 7 also serves as the upper limit of the rearward opening in the wedge member 3 and can thus serve as an abutment for the nose 11' of the bearing eye 11.

As may be seen from Figures 2 and 3, the lower wedge member may be provided adjacent the slideway 3 with an upwardly projecting flange 23 in order to receive the collapsing parts of the framework without damage to the coupling rod 8.

I claim:

1. In a socket for a pit prop comprising two wedge members slidably mounted one above the other, said members releasably coupled together in the use position by a coupling rod which after release of the locking member is movable into the uncoupling position by raising the head of the coupling rod, said coupling rod projecting from the front face of the upper wedge member, the head of the said coupling rod provided with a control member, said control member cooperating with a locking member and projecting from the underside of the head of the coupling rod when the locking member is engaged, the whole arrangement being such that by striking a blow on the underside of the head the coupling rod is first unlocked by driving up the control member and thereafter the coupling is disengaged.

2. A socket as claimed in claim 1, the upper end of the said locking member linked to the front face of the upper wedge member and supported in compression in the locking position with its lower end on the head of the said coupling rod.

3. A socket as claimed in claim 1, the opening in the rear wall and in the floor of the said upper wedge member through which the said coupling rod passes, being narrower than the head of the said coupling rod, so that when the coupling is released the head serves to retain the upper wedge member.

4. A socket as claimed in claim 1, the opening in the rear wall of the said lower wedge member through which the said coupling rod passes, so bounded by an abutment member, and the bearing eye of the said coupling rod, through which the securing bolt passes, provided with a nose, said nose so proportioned and arranged that if any deformation of the securing bolt takes place the said nose of the coupling rod bears against the abutment member and thus relieves the bolt of load.

5. A socket as claimed in claim 1, the said lower wedge member provided adjacent the slideway for the upper wedge member with an upwardly projecting protective flange, in order to arrest collapsing parts of the frame without damage to the coupling rod.

6. In a socket for a pit prop comprising two wedge members slidably mounted one above the other, said members releasably coupled together in the use position by a coupling rod which after release of the locking member is movable into the uncoupling position by raising the head of the coupling rod, said coupling rod projecting from the front face of the upper wedge member, the head of the said coupling rod provided with a control member, said control member cooperating with a locking member and projecting from the underside of the head of the coupling rod when the locking member is engaged, the upper end of the said locking member linked to the front face of the upper wedge member and supported in compression in the locking position with its lower end on the head of the said coupling rod, this head of the coupling rod provided with an opening in the region of the place of support, the said control member projecting from below into said opening and being so constructed and arranged that in its unlocking motion through

the opening it forces the control member out of engagement with the head of the coupling rod, the whole arrangement being such that by striking a blow on the underside of the head the coupling rod is first unlocked by driving up the control member and thereafter the coupling is disengaged.

7. A socket as claimed in claim 6, the said head of the coupling rod provided with a bar in which a bolt-shaped control member is mounted for up and down movement, the upper head of the said control member co-operating with the lower end of the locking member.
